(57) CLAIM

The ornamental design for an arm sleeve attachment, as shown and described.

DESCRIPTION

FIG. 1 is a front perspective view of an arm sleeve attachment in a position of use;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof showing my design. The user shown in broken lines represents the environment that forms no part of the claim. The rectangle featured in broken lines is a portion of the article that forms no part of the claim.
